INVENTOR.
John Krumholz,
BY Geo. P. Kimmel.

ATTORNEY.

UNITED STATES PATENT OFFICE

JOHN KRUMHOLZ, OF MINEOLA, NEW YORK

ROOF BRACKET

Application filed July 31, 1928. Serial No. 296,438.

This invention relates to a roof bracket, and has for its object to provide, in a manner as hereinafter set forth, a bracket of such class constructed and arranged to enable one to 5 expeditiously build a scaffold on a slanting roof and with the brackets and cross boards of the scaffold detachably and firmly held in position relatively to each other without the employment of bolts, screws and nails.

10 A further object of the invention is to provide, in a manner as hereinafter set forth, a roof bracket formed of a plurality of sections having coacting interengaging means for detachably connecting them together, and further including means for retaining and supporting a scaffold cross board or run board 15 transversely thereof.

Further objects of the invention are to provide, in a manner as hereinafter set forth, a 20 roof bracket which is simple in its construction and arrangement, strong, durable, compact, thoroughly efficient in its use, expeditiously positioned with respect to a roof, thoroughly efficient in its use, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the 35 claims hereunto appended.

In the drawings wherein like reference characters denote corresponding parts throughout the several views:

Figure 1 is a fragmentary view in elevation 40 of a structure showing the adaptation with the roof thereof of a roof bracket in accordance with this invention.

Figure 2 is a fragmentary view in plan, of 45 two of the brackets having a cross board or run board detachably supported thereby.

Figure 3 is a perspective view, broken away, of a lower section of the bracket.

Figure 4 is a fragmentary view, in perspective and broken away of a top section of the 50 bracket.

A roof bracket, in accordance with this invention includes a top or upper section and one or more bottom or lower sections. Each of the sections of the bracket can be of any desirable length.

The top section is indicated generally at 1 and which comprises a flat bar 2 torsionally twisted, intermediate its ends, as at 2' to provide an upper part 3 disposed at right angles with respect to the lower part 4 of the bar 2. 55 The twist in the bar 2 positions the upper part 3 thereof substantially at the longitudinal median of the lower part 4. The free or upper end of the part 3 of the bar 2 is bent to provide a hook-shaped terminal 5 for the 60 purpose of connecting the section 1 to that side 6 of the roof of the structure 7 opposite the side 8 upon which the bracket is positioned. The lower part 4 of the bar 2 has secured to its outer face, by the holdfast devices 65 9 the lower arm 10 of a Z-iron 11. The upper arm of the iron 11 is indicated at 12 and intermediate arm at 13. The arms 10 and 12 are disposed in parallel planes and further in parallelism to the part 4. The arm 13 is disposed at right angles with respect to the part 4 to offset the arm 12 relative to said part. The arms 12, 13 and the part 4 coact to provide a socket 14 for a scaffold cross board or 70 run board 15. The part 4 below the iron 11 75 has projecting from its outer face a plurality of spaced headed studs 16 and said part 4 in proximity to its lower end has one side edge formed with a notch 17 which is positioned below the lowermost stud 16. The purpose 80 of the studs 16 and notch 17 will be presently 85 referred to.

The bracket is illustrated, by way of example, as set up with two lower sections each referred to generally at 18 and as the lower 90 sections are of like construction, but one will be described as the description of one will apply to the other. Each lower section comprises a flat bar 19 of substantial length and of a width corresponding to the width of 95 the part 4 of the section 1. The bar 19 in the upper portion thereof is formed with a plurality of spaced key-hole shaped openings 20, one arranged above the other, and pivotally connected to said bar 19, in proximity 100

to the lower opening 20 is a latch 21 provided with a right angularly disposed nose 22. One side edge of the bar 19 in proximity to the latch 21 is formed with a notch 23 to receive the nose 22 when a section 18 is detachably connected to the section 1. When a section 18 is connected to the section 1, the notch 17 of the section 1 registers with the notch 23 of the section 18 and the nose 22 of the latch 21 enters the aligning notches to prevent lengthwise shifting of the sections relatively to each other. Further the headed studs 16 of the section 1 are adapted to extend through the openings 20 in the bar 19.

Secured to the outer face of the bar 19, by the holdfast devices 24 is the lower arm 25 of a Z-shaped iron 26. The upper arm of the iron 26 is indicated at 27 and the intermediate arm at 28. The arms 25 and 27 extend in parallel planes and further are arranged in parallelism to the bar 19. The arm 28 extends at right angles to the bar 19 and offsets the arm 27 relative to said bar and the latter in connection with the arms 27 and 28 provides a socket 29 for a scaffold cross board or run board 30. The bar 19 below the iron 26 is provided with a plurality of spaced headed studs 31 and below the lower stud 31 with a notch 32 in one side edge of said bar 19. When two lower sections 18 are employed, the studs 31 of an upper section 18 coact with the openings 20 of a lower section 18 and the notch 32 of an upper section 18 registers with the notch 23 in a lower section.

When two or more brackets are employed for scaffolding across a roof, the brackets are arranged in parallelism or spaced from each other, that is to say the sections of one bracket are arranged in parallel spaced relation with respect to the sections of an adjacent bracket and with the iron 11 of one section 1 arranged in parallelism with respect to the iron 11 of an adjacent section 1, and the same arrangement is had relative to the iron 26 of one or more lower sections 18 of a plurality of brackets.

Preferably the lower section or sections 18 are of greater length than the upper section 1, but the length of the sections of the brackets can be as desired. When shingling a roof there will be sufficient clearances to push shingles underneath the brackets. When the sections of the bracket are detachably connected together, the upper end of a lower section is mounted upon the lower end of an upper section. The studs and key-hole shaped openings, in connection with the latches 21 and notches provide means for latching the sections of the bracket together whereby they cannot shift laterally or longitudinally with respect to each other.

It is thought the many advantages of a roof bracket, in accordance with this invention, can be readily understood, and although

the preferred embodiment of the invention is as illustrated and described, yet it is to be understood that changes in the details of construction can be had which fall within the scope of the invention as claimed.

What I claim is:

1. A roof bracket comprising a plurality of sections, each of said sections including a flat bar having secured to its outer face, intermediate its ends means to provide in connection therewith a scaffold board support, one of said bars at one end portion having key-hole shaped openings and the other of said bars at one end portion having headed studs coacting with the openings to detachably connect a portion of one of said bars upon a portion of the other of the bars, each of said bars provided at said end portion with a notch, said notches aligning when said end portions are detachably connected together, a pivoted latch carried by one of said bars for extension in said aligning notches to prevent lengthwise shifting of the bars relatively to each other when said end portions are detachably connected together, and one of said bars having its other end portion of hook-like form.

2. A roof bracket comprising a plurality of sections, each including a flat bar having secured to its outer face, intermediate its ends a Z-iron providing in connection with the bars a scaffold board support, each of said bars having a notch at one side thereof in proximity to one end thereof, one of said bars at one end portion having key-hole shaped openings and the other of said bars at one end portion having headed studs coacting with the openings to detachably connect a portion of one of said bars upon a portion of the other of said bars and to provide for the aligning of said notches, a pivoted latch carried by one of said bars for extension into said aligning notches, to prevent lengthwise shifting of the bars relatively to each other when said end portions are detachably connected together, and one of said bars having its other end portion of hook-like form.

3. A roof bracket comprising a plurality of sections, each including a flat bar having secured to its outer face, intermediate its ends a Z-iron providing in connection with the bars a scaffold board support, each of said bars having a notch at one side in proximity to an end thereof, one of said bars at one end portion having key-hole shaped openings and the other of said bars at one end portion having headed studs coacting with the openings to detachably connect a portion of one of said bars upon a portion of the other of said bars and to provide for the aligning of said notches, a pivoted latch carried by one of said bars for extension into said aligning notches to prevent lengthwise shifting of the bars relatively to each other when said end portions are detachably connected together,

and one of said bars having its other end portion torsionally twisted and formed with a hook disposed at the longitudinal median of such bar.

5 4. A roof bracket comprising an upper and a lower section, each of said sections including a flat bar having secured to its outer face, intermediate its ends an angle iron to provide in connection with the bar a scaffold board support, the bar of said upper section having a notch at its side in proximity to its lower end and the bar of said lower section having a notch in its side in proximity to its upper end, one of said bars at one end 10 portion thereof having key-hole shaped openings and the other of said bars at one end portion thereof having headed studs coacting with the openings to detachably connect said portion of one of said bars upon a portion of 15 the other of said bars and to provide for the aligning of said notches, and a pivoted latch mounted upon one of said bars and provided with a nose for extension in said aligning notches to prevent lengthwise shifting of the 20 bars relatively to each other when said portions are connected together, and one of said bars having its other end portion of hook-like form.

5. A roof bracket comprising an upper and 30 a lower section, each of said sections including a flat bar having secured to its outer face, intermediate its ends an angle iron to provide in connection with the bar a scaffold board support, the bar of said upper section having a 35 notch in its side in proximity to its lower end and the bar of said lower section having a notch in its side in proximity to its upper end, one of said bars at one end portion thereof having key-hole shaped openings and the 40 other of said bars at one end portion thereof having headed studs coacting with the openings to detachably connect a portion of one of said bars upon a portion of the other of said bars and to provide for the aligning of said 45 notches, and a pivoted latch mounted upon one of said bars and provided with a nose for extension in said aligning notches to prevent lengthwise shifting of the bars relatively to each other when said portions are connected 50 together, one of said bars having its other end portion torsionally twisted and formed with a hook disposed at the longitudinal median of such bar.

In testimony whereof, I affix my signature
55 hereto.

JOHN KRUMHOLZ.
